WEB SUPPLY MECHANISM FOR PRINTING MACHINES

**Albert J. Horton, White Plains, N. Y., assignor to
R. Hoe & Co., Inc., New York, N. Y., a corpora-
tion of New York**

Application March 12, 1936, Serial No. 68,368

12 Claims. (Cl. 242—58)

This invention relates to web supply mechanisms used with machines adapted to operate upon a web, such as certain types of printing machines. More particularly the invention relates to an adjustable stop mechanism for web roll supporting reels, provided with high speed roll changers.

The web supply mechanisms and high speed roll changers, particularly referred to, are adapted to position a web replacement roll in proper relation with respect to a running web from an expiring web roll that web joining mechanism may be efficiently operated to join the web of the replacement roll to the running web without stopping or otherwise interfering with the machine operation. As the position of the replacement roll in respect to the running web would vary if the roll supporting reel was stopped at a definite position each time it was rotated to bring a roll into position due to differences in diameter of the replacement roll, it is desirable to change the stopping point of the reel in accordance with the diameter of the roll being positioned.

In view of the above desideratum, this invention has for its principal object the provision in a web supply mechanism of an adjustable stop mechanism for the web roll reels, which is adapted to be manually set in accordance with the measured diameter of the roll supported on the reel to control the rotation of the reel and stop it in proper position to dispose the roll in proper web joining position.

Another object of this invention is to provide
35 in an adjustable stop mechanism for the above
stated use, means rotatable with the reel and
which is adjustable in accordance with the di-
ameter of a web roll, to operably engage a reel
rotation interrupting device, to actuate the same.

40 A further object is to provide an adjustable stop mechanism for an electric motor driven web roll supporting reel and which is adjustable in accordance with the diameter of the web roll on the reel, to dispose an electric switch actuating member in proper position to cause the switch to stop the reel rotating motor, and thereby the reel in the desired roll supporting position with respect to another operative device of a machine operating upon a web.

50 It is also an object of this invention to provide a web supply mechanism of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed. 5

The preferred embodiment of the invention is illustrated in the accompanying drawings, wherein:

Figure 1 is an end view of a web supply mechanism embodying the features of this invention; 10

Figure 2 is a view of a part of the same looking in the direction of the arrow 2, in Figure 1;

Figure 3 is an enlarged sectional view on line 3-3 of Figure 2;

Figure 4 is a side view of the parts shown in Figure 3;

Figure 5 is an enlarged sectional view on line 5-5 of Figure 2 with an end plate broken away to expose parts covered thereby.

Figure 6 is a top view of the parts shown in 20
Figure 3.

Figure 7 is a sectional view on line 7—7 of Figure 5; and

Figure 8 is a schematic illustration of an electrical circuit adapted for use with the features 25 of this invention.

The web supply mechanism selected to illustrate the application and use of the features of this invention is particularly adapted for use with printing machines through which a web is continuously run for operation thereon of the several parts and devices thereof. The web, indicated in dotted lines at 11 in Figure 1, normally feeds from a roll 12 positioned as shown, the surface speed of which is controlled by a driven belt 13 whereby proper tension is imposed upon the web, it being understood that the belt 13 is driven from, and substantially in synchronism with, the operating machine's parts. The roll 12 together with, in this instance, a spare roll 14 and an expiring web roll 15 is mounted upon respective arms 16, 17 and 18 of a reel 19.

When the supply of web on the roll 12 is substantially exhausted, the reel 19 is rotated to position the spare roll 14 in place of the roll 12. 45 The expiring web roll therefore assumes the position of the roll 15, and the web from this roll 15 runs into the machine as shown at 11' in full lines in Figure 1. Considering now, that the roll 12, as shown, is the replacement roll, the 50 roll 15 is the expiring roll and the roll 14 is the spare roll, it is necessary to join the web of the roll 12 with the running web 11' and provision for so doing is shown as part of the web supply mechanism. The web joining mechanism in- 55

cludes swingably mounted web deflecting and severing means herein shown respectively as a brush 21 and a web cutting knife housed in a carrier 22. When it is desired to join the webs, a handle 23 is depressed and through a cable 24 swings the brush 21 towards the roll 12, pressing the web 11' thereagainst, whereupon the web adheres to the end of the web of the roll 12, which was previously prepared, including the application of an adhesive thereto. Substantially simultaneously with the joining of the webs, the web 11' running from the roll 15 is severed below the join and the web is then fed into the machine from the roll 12.

15 As the amount of the deflection of the web 11' by the brush 21 to cause it to engage the web of the roll 12, as indicated at 25 in Figure 1, is required and preferred to be the same in all instances when a web join is made in order to 20 make a proper join in the most efficient manner, it is necessary that provision be made to compensate for differences in the diameters of different web replacement rolls, when such occur. It is, therefore, contemplated to accomplish this result by the provision of adjustable means whereby the amount the reel 19 is rotated to position the replacement roll 12 may be controlled and its movement arrested when the proper position of the roll 12 with respect to the web 11' is 30 reached.

As illustrated herein the reel 19 is rotated by an electric motor 31 through a worm-gear 32, a worm-wheel 33, a shaft 34, a pinion 35, and a gear 36 secured upon a reel shaft 37. The reel 35 shaft 37, in this instance, is journaled in and extends between bearing brackets 38 and 39, each of which is secured respectively to opposing machine frame members 41 and 42. The motor 31, adapted through the aforesaid gearing to rotate 40 the reel 19, is under the control of suitable electrical solenoids, switches and relays mounted in a control box 43 and it receives its power from the conductors L1, L2 and L3 leading thereto, see Figure 8. Direction of rotation coils 44 and 45 disposed in the box 43 when energized respectively cause rotation of the motor 31 forward and reverse. A normally closed circuit limit switch 46 mounted for convenience upon the bracket 38 is herein shown connected by a conductor 47 to a line wire LL1 and by a conductor 48 to the common terminal 49 for the coils 44 and 45. Suitable switches are provided in a switch box 51 whereby the proper one of the coils 44 and 45 may be energized to cause the 50 actuation of the proper motor controls in the box 43 to rotate the motor 31 in the desired direction, the switches in box 51 being connected to line wire LL2 by a conductor 52. Conductors 53 and 54 leading from the box 51 may be connected 55 to the switches therein and to controls of other operable parts of the mechanism such as the web joining mechanism controls (not shown) and a suitable tensioning device operable upon a floating roller 55 over which the web is threaded 60 in its passage through the machine, so as to prevent operation of the reel motor 31 when these devices are in operation or vice versa.

Secured upon and rotatable with the reel shaft 37, herein shown disposed adjacent the bearing bracket 38, is a device 61, see Figures 3-7 inclusive, circular platelike in form, which is adapted by means of a lug 62 to actuate the limit switch 46 when the reel is rotated into a determined position, the lug 62 being adjustable circumferentially about the device 61 by means of T-bolts

63 carried by the lug 62 and disposed in T-slots 64 in a casing member 65 of the device 61. A cover plate 66 is secured to the casing 65 and is provided with a central hub 67 which encircles the shaft 37 and is secured thereto by set screws 68. Both the casing member 65 and the cover plate 66 are formed of semi-disc-like portions which respectively are secured together by screws 69 and 71. The central hub 67 of the plate 66 is provided with an annular flange 72 at one 10 end, and a hub 73 provided on the casing 65 surrounds the hub 67 and is rotatably retained thereon by the flange 72.

The casing member 65 and the plate 66 are 15 adjustably connected together for rotation in unison by means of one of a plurality of triangular studs 74, the number of studs corresponding to the number of roll carrying arms on the reel 19. Each stud 74 is locked to the plate 66 by a nut 75, one edge of each stud 74 being engageable 20 with teeth 76 formed in a segment piece 77. The segment piece 77 is mounted upon a lever 78 which is pivoted at 79 to the casing member 65 between the same and the plate 66. The lever 78 is provided with a thumb engageable part 81, 25 which extends from the lever 78 into a recess 82 formed in the peripheral wall of the casing 65 and open thereat to permit ready access to the thumb part 81. Depression of the lever 78 by pressure upon the part 81 releases the engagement between the stud 74 and the teeth 76 of the segment 77 whereby the casing 65 may be rotated about, and relatively to, the plate 66. A compression spring 80 having one of its ends abutting a post 83 secured to the casing 65 and 35 its other end abutting a collar 84 fastened to a guide rod 85 which is secured to the free end of the lever 78, continuously urges the lever 78 outwardly insuring engagement of the teeth 76 on the segment 77 with the stud 74 until the lever 40 is depressed to release the same.

A plate 86 having indicia thereon, which proportionally corresponds to various diameters of web rolls is provided and mounted on the periphery of the casing 65. Herein the indicia comprises a series of lines 87 which are spaced apart along the plate 86 and are numbered in accordance with the diameter in inches of the web rolls to be mounted on the reel 19. A point mark 88 is provided on the periphery of the plate 66 which, when its position with respect to any line 87 is considered, visually indicates the setting, that is, the relative rotative position of the casing 65 in respect to the plate 66, and thereby the position of the switch actuating lug 62 in respect to 50 the arm of the reel 19 carrying the replacement web roll 12.

The operation of the adjustable stop mechanism above described is easily and efficiently accomplished. The operator measures the diameter of the replacement web roll 12 while preparing it for having its web joined to the running web 11'. Before the reel 19 is rotated to position the roll 12, the thumb part 81 is depressed and the casing 65, with the lug 62, is rotated 55 about the plate 66 until the point mark 88 is opposite the line 87 numbered in accordance with the roll diameter as above ascertained. Release of the part 81 locks the casing 65 to the plate 66 and the mechanism is set for efficient operation. 60 Rotation of the reel 19 will now be limited to properly position the roll 12 in respect to the running web 11' as shown at 25 due to the interruption of the actuation of the motor by the 65 opening of the limit switch 46 by the lug 62. By 70 75

the provision of the above described adjustable stop mechanism in combination with the other operative devices in a web supply mechanism, the latter becomes more serviceable and efficient 5 in its use and is of generally improved construction, and the web roll support may be actuated to properly position any roll of a diameter within the range of the permitted setting with respect to a running web. The mechanism herein disclosed and described is particularly efficient for 10 the purposes contemplated including the stopping of the roll supporting reel at a point in accordance with the diameter of the supported roll.

15 It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

25 What I claim is:

1. In combination, a pair of arms adapted to rotatably support a web roll and being mounted upon a shaft, means to rotate said shaft, means to control the amount of rotation of said shaft, 30 and means to actuate said control means including a part releasably connectable to said shaft, and means to adjust said part on said shaft and relatively to said arms in accordance with the diameter of the supported roll on said arms, 35 whereby said control actuating means will actuate said control means to stop the rotation of said shaft when the supported roll reaches a predetermined position.

2. In a stop mechanism for a rotatable web roll 40 supporting reel having a plurality of roll supporting arms, means to rotate said reel, means to control said reel rotating means to interrupt the rotation of said reel, and means to actuate said control means including a part releasably connectable to said reel for rotation therewith and adjustable relatively to any one of the roll supporting arms in accordance with the diameter of the roll on the selected arm to actuate said control means and cause it to interrupt the rotation of said reel when the roll on the selected arm is in a predetermined position.

3. In combination with a rotatably mounted plurality of web roll supporting arms, means to rotate said arms about a common axis, and means 55 to control the amount of rotation of said arms to selectively position any one of them in a predetermined position, said last means including a part rotatable about the aforesaid common axis and selectively adjustable in respect to any one of 60 said arms and in accordance with the diameter of the roll supported by the selected arm.

4. In combination with a rotatably mounted plurality of web roll supporting arms, common means to control the amount of rotation of 65 said arms to selectively position any one of them in a predetermined position, said common means including a part selectively positionable relatively to any one of said arms and being adjustable in accordance with the diameter of the roll 70 on the selected arm.

5. In a stop mechanism for a rotatable web roll supporting reel having a plurality of arms, a shaft for said reel, means to rotate said reel, and a part in control of said rotating means to 75 actuate the same and interrupt the rotation of

said reel, means to drivingly connect said part relatively to any one of said arms for rotation with said reel, and means to adjust said part in accordance with the diameter of the roll on the selected arm when connecting it for rotation with said reel whereby the rotation of said reel will be interrupted to position the selected arm in predetermined roll supporting position. 5

6. In a stop mechanism for a rotatable web roll supporting reel, a rotatably mounted control 10 actuating member, a rotatable part to which said member is circumferentially and adjustably connectable, and means to connect said part to said member including means adjustable in accordance with the diameter of a web roll on said reel. 15

7. In an adjustable stop mechanism for a rotatable web roll supporting reel having a shaft, means to interrupt the rotation of said reel, a casing rotatable about said shaft and having a part adapted to actuate said reel rotation interrupting means, a plate secured to and rotatable with said shaft, and means to adjustably and drivingly connect said casing and said plate in accordance with the diameter of the web roll supported on said reel. 25

8. In an adjustable stop mechanism for a rotatable web roll supporting reel having a shaft, means to interrupt the rotation of said reel, a casing rotatable about said shaft and having a part adapted to actuate said reel rotation interrupting means, a plate secured to and rotatable with said shaft, and manually releasable means to adjustably and drivingly connect said casing and said plate in accordance with the diameter of the web roll supported on said reel, said 30 means including a toothed lever on one and a tooth engaging part on the other. 35

9. In an adjustable stop mechanism for a rotatable reel having a shaft and a plurality of web roll supporting arms, means to rotate said 40 shaft, means to interrupt the rotation of said shaft, a casing mounted for rotation about said shaft, a part connected to said shaft for rotation therewith, and means to connect said casing to said part relatively to any one of said arms, said 45 connecting means being adjustable in accordance with the diameter of the web roll on the selected arm. 50

10. In an adjustable stop mechanism for a rotatable reel having a shaft and a plurality of web roll supporting arms, means to rotate said 55 shaft, means to interrupt the rotation of said shaft, a casing mounted for rotation about said shaft, an actuating member for said shaft rotation interrupting means on said casing, a part connected to said shaft for rotation therewith, means to connect said shaft to said part to position said actuating member relatively to any one of said arms, said connecting means being adjustable in accordance with the diameter of the web roll on the selected arm. 60

11. In an adjustable stop mechanism for a rotatable reel having a shaft and a plurality of circumferentially spaced apart web roll supporting arms, means to interrupt the rotation of said reel, a casing, a plate having a hub portion upon which said casing is rotatably mounted, said plate being secured to and rotatable with said shaft, and releasable means to drivingly connect said casing and said plate comprising a toothed lever on one and a plurality of toothed engaging members on the other, said tooth engaging members being circumferentially spaced apart in accordance with the spacing of said arms, said toothed 70 75

lever and any one of said tooth engaging members being adjustable in respect to each other in accordance with the diameter of the supported roll on the one of said arms corresponding to the 5 respective one of said tooth engaging members.

12. In a control mechanism for a rotatable web roll supporting reel for a machine operating upon a web, a reel rotation control, a pair of cooperating relatively rotatable members, a reel rotation 10 control actuating part on one of said members,

means to adjustably connect said members together, indicating means on one member corresponding to various web roll diameters, and an indicating point on the other member cooperating with the indicating means to denote the adjustment required between said members to position said control actuating part relatively to said control in accordance with the diameter of the supported web roll. 5

ALBERT J. HORTON. 10
